FIG. 4.

FIG. 5.

Inventor
Edward J. Miller,
By Hugh H. Wagner,
Attorney.

UNITED STATES PATENT OFFICE.

EDWARD J. MILLER, OF JENNINGS, MISSOURI, ASSIGNOR TO ST. LOUIS SCREW COMPANY, OF ST. LOUIS, MISSOURI, A CORPORATION OF MISSOURI.

ELECTROPLATING-MACHINE.

1,206,122.

Specification of Letters Patent. Patented Nov. 28, 1916.

Application filed June 18, 1918. Serial No. 103,942.

To all whom it may concern:

Be it known that I, EDWARD J. MILLER, a citizen of the United States, and resident of Jennings, St. Louis county, in the State of Missouri, have invented new and useful Improvements in Electroplating-Machines, of which the following is a full and complete specification, reference being had therein to the accompanying drawings.

10 This invention relates to an electro-plating machine and it has for its object to provide an improved device of this character constructed in such manner that the work will be automatically and positively turned during its passage through the plating solution.

15 I am aware of the fact that it has heretofore been proposed to turn the work during the time of plating, but in all of the machines with which I am familiar the methods employed to secure this result are uncertain, particularly on small flat work such as washers or the like.

20 A further object of the invention is to provide for such an adjustment of the machine during the passage of the work therethrough that the time required for the articles to pass through the plating solution may be varied at will.

25 Further objects and advantages of the invention will be set forth in a detailed description which now follows:

30 In the accompanying drawings, Figure 1 is a longitudinal sectional view of an electro-plating machine constructed in accordance with the invention; Fig. 2 is a transverse sectional view of said machine; Fig. 3 is a detailed view in side elevation of one of the members employed for adjusting the inclination 35 of the work-retaining drum; Fig. 4 is a detailed longitudinal sectional view of the entrance end of the machine; and Fig. 5 is a like view of the discharge end of the machine.

35 In the accompanying drawings 5 designates a solution tank, this tank serving to receive the plating solution. Brackets 6, only one of which is shown, support a transverse shaft 7 and this shaft in turn supports a feed-pan 8 in such manner that this 40 pan may be jiggled by a cam 9 that is mounted upon a transverse shaft 10. This shaft is driven by means of pulleys 12 and 13 and a belt 14 from a drive shaft 15. The 45 drive shaft 15 carries a worm 16 which

meshes with a worm-wheel 17 that is carried by a work-retaining drum 18. Ring-like members 19 provide tracks or ways 20 which rest upon rollers 21 that are carried by frames 22 and upon which rollers the work-retaining drum 18 is mounted for rotation.

50 Work placed within the pan 8 is discharged slowly from the right-hand end of said pan upon a chute 23, said chute being carried by supports 24 and having its discharge end arranged to discharge the work into the work-retaining drum 18.

55 During the rotation of drum 18 the work travels from the entrance end of the drum to the discharge end thereof, this traveling of the work being due to the inclination of the drum. This inclination of the drum with relation to the horizontal may be secured either by inclining the tank as a whole or by inclining the drum with relation to the tank. An adjustable inclination of the tank as a whole is rendered possible by providing brackets 25 upon the tank which carry adjusting screws 26, said screws bearing upon brackets 27, only one of which is shown, 60 these brackets 27 being mounted upon the opposite ends of a cross-bar 28.

65 It is apparent that by screwing down upon screw 26 the right-hand end of the tank in Fig. 1 will be elevated or if said screw is turned in the opposite direction the right-hand end of the tank will be lowered, and the degree to which the right-hand end of the work-retaining drum is lowered with relation to its left-hand end will determine 70 the rate of travel of the work through the drum and will consequently determine the length of time required for any given article to pass through the plating process.

75 For varying the inclination of the drum with relation to the tank, the right-hand frame ends 22 which carry the rollers 21 are provided at their upper ends with eccentrically mounted cams 29 which bear upon brackets 30 carried by the tank 5. 100 These cams provide for the necessary limited adjustment of the right-hand end of the drum 18.

80 The articles discharged from chute 23 into the drum 18 are picked up by longitudinal ribs 31 of drum 18 and carried around with the drum and rib until the center of gravity of any individual article is outside the rib by which it is carried, whereupon the article falls, and in doing so it turns itself, 110

owing to its center of gravity being without the rib 31. It will, of course, be understood that the articles will be picked up in this manner a number of times before they 5 are finally discharged from the right-hand end of the drum. When discharged from the drum they fall upon a conveyer belt 32 which passes over pulleys 33 and 34 and carries transverse ribs 35, which ribs engage 10 the articles and carry them upwardly and discharge them over the pulley 34 into any suitable receptacle, such as a washing receptacle (not shown). The anode of the apparatus is indicated at 36 (and may consist 15 of a series of anodes) and is supported preferably centrally within the drum by adjusting rods 37 and 38, said rods being threaded into heads 39 and 40 of the anode. Adjusting nuts 41 and 42 are threaded upon the 20 upper ends of these rods and are provided with operating handles 43 and 44. The anode 36 carries an insulating element 45 so that this element is bodily adjustable with the anode, and said insulating element 25 prevents the passage of the current in lines away from the work and renders the line of least resistance to the electrical current at that point where it will most efficiently act upon the articles being plated. This insulating element further obviates the possibility of a short circuit being caused by any 30 article being caught upon the anode.

Current is supplied to the anode through a cable or bus-bar 46. This current passes 35 from the anode and through the solution to drum 18 and thence to commutators 47 carried by said drum.

Brushes 48 are held in contact with the commutators by springs 49, said springs 40 surrounding rods 50 by which the brushes are carried.

A cathode connecting cable or bus-bar 51 is secured within heads 52 of the rods 50.

While the elements shown and described 45 are well adapted to serve the purpose for which they are intended, it is to be understood that the invention is not limited to the precise construction set forth, but that it includes within its purview such changes 50 as come within either the spirit or the terms of the appended claims.

Having described my invention what I claim is:

1. In an electro-plating machine, a solution case, a rotatable drum longitudinally suspended therein, an anode or anodes ex-

tending through said drum, and means for imparting movement to said anode or anodes toward and away from the center of said drum. 60

2. In an electro-plating machine, a solution case, a frame in each end of said case, a rotatable drum carried by said frames, and means for lowering and raising either end of said drum. 65

3. In an electro-plating machine, a solution case, a rotatable drum extending longitudinally therethrough, and a cam carried by said case adapted to impart vertical movement to one end of said drum. 70

4. In an electro-plating machine, a solution case, a frame in either end of said case, a rotatable drum carried by said frame, and means for imparting vertical movement to said frame. 75

5. In an electro-plating machine, a rotatable drum, an anode or anodes extending therethrough, means carried by said drum for engaging the articles to be plated, and means for reciprocally moving said anode 80 or anodes in a vertical line. 85

6. In an electro-plating machine, a solution case, a frame carried in each end of said case, a rotatable drum carried by said frames, an anode or anodes extending longitudinally therethrough, and cams carried by said case and adapted to impart vertical movement to one end of said drum. 90

7. In an electro-plating machine, a solution case, a rotatable drum mounted therein, 95 an anode or anodes extending through said drum, means for moving said anode or anodes toward and away from the center of said drum, and members carried by said drum for engaging the articles to be plated. 95

8. In an electro-plating machine, a solution case, a rotatable drum suspended longitudinally therein, an anode or anodes extending through said drum, an insulating guard disposed at one side of said anode or 100 anodes, and means for imparting movement to the said anode or anodes and insulating guard toward and away from the center of said drum.

9. In an electro-plating machine, a solution case, a rotatable drum carried longitudinally therein, and means for imparting vertical movement to either end of said drum. 105

In testimony whereof I affix my signature. 110

EDWARD J. MILLER.
